(57) **CLAIM**

The ornamental design for a storage console, as shown and described.

DESCRIPTION

FIG. 1 is a perspective view of a storage console, according to the present invention;

FIG. 2 is a front elevational view of the storage console of FIG. 1;

FIG. 3 is a rear elevational view of the storage console of FIG. 1;

FIG. 4 is a left side elevational view of the storage console of FIG. 1;

FIG. 5 is a right side elevational view of the storage console of FIG. 1;

FIG. 6 is a top plan view of the storage console of FIG. 1;

FIG. 7 is a perspective view of a storage console, according to the present invention;

FIG. 8 is a rear elevational view of the storage console of FIG. 7;

FIG. 9 is a front elevational view of the storage console of FIG. 7;

FIG. 10 is a left side elevational view of the storage console of FIG. 7;

FIG. 11 is a right side elevational view of the storage console of FIG. 7; and,

FIG. 12 is a top plan view of the storage console of FIG. 7.

The dashed lines in the Figures are for environmental

purposes only and do not form a part of the claimed design.
